EXPANSIBLE BRACELET OR SIMILAR ARTICLE

Saul Ritter, New York, N. Y.

Application November 29, 1949, Serial No. 6,315

Term of patent 14 years

(Cl. D45—4)

To all whom it may concern:

Be it known that I, Saul Ritter, a citizen of the United States, residing at 101 Central Park West, New York city, New York, have invented a new, original, and ornamental Design for an Expansible Bracelet or Similar Article, of which the following is a specification, reference being had to the accompanying drawing, forming part thereof.

Fig. 1 is a top plan view of an expansible bracelet embodying my new design, the links shown in full lines being repeated throughout the length of the bracelet as indicated by the broken lines;

Fig. 2 is a side elevational view of one end of the expansible bracelet;

Fig. 3 is a bottom plan view of the bracelet as shown in Fig. 1; and

Fig. 4 is a top plan view of one end of the bracelet illustrating the links in an expanded position.

I claim:

The ornamental design for an expansible bracelet or similar article, as shown and described.

SAUL RITTER.
